DETACHABLE ELECTRICAL CONNECTOR
HAVING TERMINAL CLAMPING MEANS

Mervyn R. Rathborne, Half Moon Bay, Calif.

Application June 9, 1952, Serial No. 292,455

18 Claims. (Cl. 339—76)

1

This invention relates to quick-detachable electrical connectors to be employed with electrical or electronic devices, such as household appliances and radio or television sets, which employ electric power supply couplings, including metallic prongs or plugs and receptacles or sockets into which such prongs or plugs are adapted to be quickly inserted or from which they may be readily withdrawn.

An important object of the invention is to provide electrical connectors which establish and maintain good electrical connections of low and substantially unvarying resistance.

Another important object is to provide electrical connectors which provide strong mechanical joints between each prong or plug, attached to the power supply conductors, and each contact or terminal within the receptacle or socket into which each prong or plug is inserted.

Still another important object is to provide electrical connectors which employ a positive mechanical wedging action as means to couple each connector prong or plug to its associated terminal or contact.

A further important object is to provide electrical connectors as last described which permit each wedged prong or plug to be quickly and easily disengaged from its associated terminal or contact.

In both cases, the plugs or prongs are all wedged at the same time and all disengaged at the same time.

Furthermore, an important object is to provide such electrical connectors which do not deteriorate with extended use. The new connectors are not dependent for their action upon the pressure or tension produced by a coil spring. Therefore, the possibility of a loose or faulty connection between the prongs of a male plug and the contacts or terminals of a female connector, due to wear upon or deterioration of a coil spring, does not occur. Arcing, due to faulty connections, is substantially eliminated.

Additionally, an important object is to provide electrical connectors which securely wedge a conventional two-wire appliance plug or cap into a screw-type socket or conventional two-wire convenience outlet and thereby tend to prevent such plug or cap from being accidentally pulled out of the socket or outlet.

Other objects and advantages of the invention will be apparent during the course of the following detailed description of the invention, taken in connection with the accompanying drawings, forming a part of this disclosure, and in which drawings:

2

Fig. 1 is a vertical section of one form of the new connector, associated with a conventional electrical socket and plug.

Fig. 2 is a vertical section of the connector of Fig. 1, taken on a line substantially 90° from that of the showing in Fig. 1, and with the socket and plug of Fig. 1 removed.

Fig. 3 is a horizontal section, substantially on the line 3—3 of Fig. 1.

Fig. 4 is a vertical section, substantially on the line 4—4 of Fig. 1.

Fig. 5 is a vertical section of resilient socket means forming portions of the new connector of Figs. 1 to 4 inclusive.

Fig. 6 is a vertical section of a second form of the new connector, associated with a conventional electrical outlet and a conventional plug.

Fig. 7 is a vertical section of the connector of Fig. 6, taken on a line substantially 90° from that of the showing in Fig. 6, and with the plug removed.

Fig. 8 is a fragmentary horizontal section, substantially on the line 8—8 of Fig. 6.

Fig. 9 is a vertical section of the new connector of Fig. 6 taken substantially on the line 9—9 of Fig. 6.

Fig. 10 is a vertical section of a resilient socket means of the new connector of Figs. 6 to 9 inclusive.

Fig. 11 is a vertical section of a third form of the new connector associated with an electrical socket and an electrical plug.

Fig. 12 is a vertical section of the new connector of Fig. 11, taken on a line substantially 90° from that of the showing in Fig. 11 and with the socket and plug removed.

Fig. 13 is a horizontal section of the connector of Fig. 11, substantially on the line 13—13 of Fig. 11.

Fig. 14 is a vertical section, substantially on the line 14—14 of Fig. 11.

In the drawings, wherein for the purpose of illustration are shown three forms of the invention and wherein similar reference characters designate corresponding parts throughout the several views, the letter A designates the new electrical connector of Figs. 1—5 inclusive; B and C, electrical couplings which may be associated therewith, by way of example; D, the form of the new connectors as shown in Figs. 6—10 inclusive; E and F, electrical couplings which may be associated therewith, by way of example; G, another form of the new connectors, as shown in Figs. 11—14 inclusive; and H and K, electrical couplings which may be associated with this form, by way of example.

The new electrical connector A includes a rotatable operating ring or tubular member 15 providing a wall 16, the outer periphery of which is adapted, as by providing knurling, for grasping by one hand of the user for rotation thereof, and the inner periphery is provided with means for rotatable connection of a wedging cylinder 26 of a wedging member assembly 25 (to be subsequently described) with the operating ring 15. This means is preferably screw threads 17 of the operating ring 15 and screw threads 27 of the wedging cylinder 26.

At the end face 18 of the operating ring 15 there may be provided a bead 19 extending outwardly therefrom, and the other end face 20 may be bevelled.

The wedging member assembly 25 includes a wedging cylinder 26, less in length than that of the operating ring 15, and less in diameter than the interior diameter of the operating ring, with exterior screw threads 27 in its periphery to co-operate with the screw threads 17. This cylinder 26 has opposite substantially flat parallel faces 28 and 29. The wedging member assembly 25 also includes a first disc 30 provided with a plurality (as two) of spaced-apart appliance plug prong-receiving slots or openings 31, extending therethrough from its outer face 32, and the disc 30 engages the operating ring 15, at its bevelled end face 20. Furthermore, the wedging member assembly 25 includes a second disc 33, with suitable openings therethrough from its outer face 35 for electrical conductor means to be subsequently described. This disc 33 engages the operating ring at its beaded end face 18, with the wedging cylinder 26 between the two axially-aligned discs 30 and 33, and the discs and wedging cylinder are inter-connected as by connecting means comprising for example, a pair of rivets 34 (Fig. 2) with an end enlargement of each within suitable recesses 36 in the face 32 of the disc 30 and the opposite end enlargement of each within suitable recesses 37 in the face 35 of the disc 33 and the shanks of the rivets extending through suitable bores 38, in the discs and wedging cylinder, connecting the recesses 36 and 37. The fit of the shanks in the bores of the discs is a force fit, but the fit in the wedging cylinder is a loose fit.

From the foregoing it is now clear that the discs 30 and 33, together with the wedging cylinder 26, move as a unit but, during such movement, the wedging cylinder 26 may travel alternately towards and away from either disc.

The wedging cylinder 26 is provided with a pair of openings 39 extending from face 28 to face 29. These openings have opposite substantially flat faces 40 which converge toward the face 28, and consequently diverge toward the first disc 30, while the other opposite faces 41 are preferably parallel to each other, as in Fig. 4. One opening 39 axially aligns with the transverse axis of one opening or slot 31 of the disc 30 and the other opening 39 axially aligns with the transverse axis of the other opening or slot 31.

Resilient socket means 45 is provided to receive the prongs 75 of an electrical coupling B, which later may include a two-pronged cap from which the prongs extend and, consequently, two of the means 45 are employed and carried by the openings 39.

Each means 45 comprises three strips of lengths 46, 47 and 48 of resilient electricity-conducting metal, as brass, of a width preferably slightly less than the width between two opposite

faces so as to prevent rubbing contact of the strips and these faces. The longer strip 46 comprises an intermediate prong-contacting portion of two substantially parallel elongated parts 49 and 50 having small rounded facing projections 51 intermediate their ends, formed by up-setting or swaging the metal so a small socket 52 is also provided back of a projection, and the spaces between these parts provide continuations, so to speak, of an associated slot 31, as in Fig. 1. The parts 49 and 50 are joined to elongated parts 53 and 54, by short parts 55 and 56. The parts 53 and 54 diverge toward the associated slot 31 and the ends of the parts 53 and 54, opposite their connections with the parts 55 and 56, are joined to a short part 59 disposed in overlapping relationship. In the spaces between an adjacent part 49 and 53 and 50 and 54 are disposed the strips 47 and 48 respectively. Each strip 47 and 48 comprises a longer portion 60 and two short portions 61 and 62. The portions 60 extend along portions of the parts 53 and 54 respectively and in face contact therewith, the portions 61 extend along the parts 55 and 56 respectively in face contact therewith and the portions 62 project across the last spaces mentioned and are adapted to extend into the small sockets 52.

The parts 53 and 54 provide reinforcements for the formed strips 46, particularly the tapered parts thereof, and bear tightly against the projections 51 when the wedging cylinder is disposed as in Fig. 1, after the prongs 75 are slipped into the slots 31 and between the parts 49 and 50 with the conventional openings in the prongs 75 accommodating the projections 51. (Each of these conventional openings accommodate two of the projections so there are good grips of the parts 49 and 50 upon the prongs; these grips being both resilient grips and latching grips.)

The free end parts of the strip 46 and the part 59 are joined by an approved electricity-conducting connecting and securing means, such as the screw 63 and the rivet 64, both of which extend through suitable openings in the disc 33, and both of which provide electric conductor means.

It will be noted that, normally, portions of the resilient socket means 45 extend through the wedging cylinder 26 and project therebeyond toward the slots 31, and the parts 53 and 54 contact the faces 39 and 40 respectively.

From the foregoing and showing in Fig. 1, it is clear that, as the wedging cylinder 26 moves toward the disc 30, upon hand rotation of the operating ring 16 the parts 53 and 54 will be progressively forced toward each other and, in turn, force the parts 49 and 50 toward each other, particularly from the projections 51 to their ends adjacent the slots 31, whereby prongs within the spaces between the parts 49 and 50 will be firmly clamped and good electrical and mechanical connections between the resilient socket means and the prongs will result.

There is shown electrical conductor means as an electrical plug 65 having the usual exterior metallic screw threads 66, providing one electric conductor and terminal and the central rivet 67 with its head 68 providing an electric conductor as well as an additional means to secure the plug body to the disc 33, in the central recess and bore 69 of this disc. The screw threads 66 are electrically connected, as by a suitable conductor strip 70 to the conductor screw 63 and the central rivet 67 is electrically connected to the rivet 64 by a conductor strip 71.

The body of the plug 65 as well as the operating ring 15, wedging cylinder 26 and discs 30 and 33 are of suitable dielectric material or materials.

Associated, by way of example, with the plug 65 is an electrical coupling C which is a conventional electric lamp socket having a central contact 80 and screw threads 81 forming the other contact and adapted to cooperate with the screw threads 66.

Referring now to Figs. 6-10 inclusive, the electrical coupling form D of the invention includes a rotatable operating ring or tubular member 115 with the wall 116 thereof having an outer periphery for grasping by the hand of the operator and its inner periphery provided with screw threads 117 to cooperate with screw threads 127 of a wedging cylinder 126 to be subsequently described, and thus providing means for rotatable connection of the ring 115 and cylinder 126. One end face 120 of the ring 115 may be bevelled.

A wedging member assembly 125 is shown and includes a wedging cylinder 126 less in length than that of the operating ring 115 and less in diameter than the interior diameter of this ring, with exterior screw threads 127 to cooperate with the screw threads 117. The cylinder has opposite, substantially parallel flat faces 128 and 129.

The wedging member assembly 125 also includes a first disc 130 provided with a plurality (as two) of spaced-apart appliance prong-receiving slots or openings 131 from the outer face 132 thereof, and a second disc or end portion 133 with suitable openings therethrough from its outer face 135 for electrical conductor means to be subsequently described, and engages the operating ring 115 at its bevelled end face 120, with the wedging cylinder 126 between the two axially-aligned discs 130 and 133 and the former and the discs are inter-connected as by connecting means comprising, for example a screw 134, with the head thereof within a suitable recess 136 in the outer face of the disc 133 and the screw threaded free end portion of the shank of the screw extending through an axial screw-threaded opening in disc 130. The shank of the screw has a firm connection with both discs, but there is a loose or free sliding connection between the wedging cylinder 126 and screw shanks where the screw shanks extend through the wedging cylinder.

From the foregoing it is now apparent that the wedging cylinder 126 moves, upon rotation of the operating ring, alternately toward and away from either disc 130 or 133.

The wedging cylinder 126, is provided with a pair of openings 139 extending from face 128 to face 129. These openings have opposite substantially flat faces 140 which converge toward the face 128, and consequently diverge toward the first disc 130, while the other opposite faces 141 are preferably parallel to each other, as in Fig. 8. One opening 139 axially aligns with the transverse axis of one opening or slot 131 of the disc 130 and the other opening 139 axially aligns with the transverse axis of the other opening or slot 131.

Resilient socket means 145 is provided to receive the prongs 175 of an electrical coupling E, which later may include a two-pronged cap from which the prongs extend and, consequently, two of the means 145 are employed and carried by the openings 139.

Each means 145 comprises three strips of lengths 146, 147 and 148 of resilient electricity-conducting metal, as brass, of a width preferably

slightly less than the distance apart of a pair of opposite faces 141 so there will be no contact of the strips and these faces. The longer strip 146 comprises an intermediate prong-contacting portion of two substantially parallel elongated parts 149 and 150 having small rounded facing projections 151 intermediate their ends, formed by upsetting or swaging the metal so a small socket 152 is also provided back of a projection, and the spaces between these parts provide continuations, so to speak, of an associated slot 131, as is clear in Fig. 6. The parts 149 and 150 are joined to elongated parts 153 and 154, by short parts 155 and 156. Parts 153 and 154 diverge toward the associated slot 131 and the ends of the parts 153 and 154, opposite their connections with the parts 155 and 156, are joined to a short part 159 and disposed in overlapping relationship. In the spaces between an adjacent part 149 and 153 and 150 and 154 are positioned the strips 147 and 148 respectively, a long portion 160 and two short portions 161 and 162. The portions 160 extend along portions of the parts 153 and 154 respectively and in face contact therewith, the portions 161 extend along the parts 155 and 156 respectively in face contact therewith and the portions 162 project across the last spaces mentioned and are adapted to extend into the small sockets 152.

The parts 153 and 154 provide reinforcements for the formed strips 146, particularly the tapered parts thereof, and bear tightly against the projections 151 when the wedging cylinder is disposed as in Fig. 6, after the prongs 175 are slipped into the slots 131 and between the parts 149 and 150 with the conventional openings in the prongs 175 accommodating the projections 151. (Each of these conventional openings accommodate two of the projections so there are good grips of the parts 149 and 150 upon the prongs, these grips being both resilient grips and latching grips.)

The free end parts of the strips 146 and the part 159 are joined by any approved electricity-conducting means, such as the bolts 163 which, with their nuts 164 are also binding posts for electrical conductors and the shanks of the bolts 163 extend through suitable openings in the disc 133 and provide electric conductor means.

It will be noted that in the gripping or closed condition of the resilient socket means 145, portions of the resilient socket means 145 extend through the wedging cylinder 126 and project therebeyond toward the slots 131, and the parts 153 and 154 contact the faces 139 and 140 respectively.

From the foregoing and showing in Fig. 6, it is clear that, as the wedging cylinder 126 moves toward the disc 130, upon hand rotation of the operating ring 115 the parts 153 and 154 will be progressively forced toward each other and, in turn, force the parts 149 and 150 toward each other, particularly from the projections 151 to their ends adjacent the slots 131, whereby prongs within the spaces between the parts 149 and 150 will be firmly clamped and there will be provided good electrical and mechanical connections between the resilient socket means and the prongs.

There is shown an electrical coupling F, which may include a pair of conductors 165 and 166 secured to the bolts 163 at the nuts 164 and all enclosed in an outlet box 167 with the disc 133 secured to the cover 168 of the box to be spaced therefrom, as by the spaces 169 and 170.

The form G of the new electrical connector

shown in Figs. 11 to 14 inclusive, includes a rotatable operating ring or tubular member 215 providing a wall 216, the outer periphery of which is adapted for hand grasping for rotation of the ring, and the inner periphery of which is provided with means for rotatable connection with a connector or plug to be subsequently described. This means includes screw threads 217 of the ring 215.

The wedging member assembly 225 includes a wedging cylinder 226 less in length than that of the operating ring 215, and less in diameter than the interior diameter of the ring 215. The cylinder has opposite substantially flat parallel faces 228 and 229.

The assembly 225 also includes a first disc 230 provided with a desired number (at two) of spaced-apart appliance plug prong-receiving slots or openings 231, extending therethrough from its outer face 232, and the disc 230 engages the operating ring 215 at one end portion of the latter. There is also a second disc 233, with suitable openings therethrough from its outer face 235 for electrical conductor means to be later described. The two discs are spaced apart, are axially aligned and the wedging cylinder 226 is disposed in the space between the discs.

The wedging cylinder 226 and discs 230 and 233 are interconnected as by connecting means comprising, for example, a pair of bolts 234 (Fig. 12) with the heads thereof within suitable spaced-apart recesses 236 in the faces 232 of the disc 230 with the screw threaded ends thereof in and extending outwardly of the disc 233 (spaced-apart, screw threaded openings in the disc being provided) and the free protruding ends of the bolt shanks being provided with suitable nuts bearing against the outer face 235. Smooth portions of the bolt shanks extend through suitable openings in the wedging cylinder 226 which openings are enlarged to open to the face 229 and receive end portions of two expansion coil springs 237, encircling portions of the shanks, and bearing at their other ends upon the inner face of the disc 230, for resiliently urging the wedging cylinder toward the other disc, and forming portions of means to cause the wedging cylinder to move toward the second disc 233 as will be subsequently explained in connection with a plunger 267 to be described.

From the foregoing it is now clear that the wedging cylinder, being of less height than the distance between the inner faces of the two discs, may travel alternately toward and away from either disc.

The wedging cylinder 226 is provided with a pair of openings 239 extending from face 228 to 229 and the openings have opposite, substantially flat faces 240 which converge toward the face 228 and, consequently, diverge toward the first disc 230, while the other opposite faces 241 of the openings are preferably substantially parallel, as in Fig. 14. The openings 239 axially align with the transverse axes of the openings or slots 231.

Resilient socket means 45 is provided for the form G, substantially like that of form A and similar reference characters are employed in designating both resilient socket means. The two means 45 are provided to receive the prongs 275 of an electric coupling H, which latter may include a two pronged-cap from which the prongs extend.

There is also shown electrical conductor means as an electrical plug 265 having usual exterior metallic screw threads 266, providing one electric

conductor and terminal and the central screw or plunger 267 with its head 268 providing an electric contact and its shank providing an electric conductor as well as means to cause the wedging cylinder to move toward the first disc 230 upon reciprocation of the plunger or screw 267 in one direction (against the tension of the springs 237) and to move toward the second disc when the screw or plunger 267 reciprocates in the opposite direction.

This plunger is secured to the wedging cylinder 226 as by screw threads cooperating with the screw threads of a central socket in the wedging cylinder, and the plunger slides through a suitable central opening in the disc 233 and also slides through a central opening in the body of the plug 265 and normally projects outwardly therefrom. The screw threads 266 are electrically connected with one conductor screw 263 as by conductor strip 270, and the other conductor screw 263 is electrically connected with the plunger 267 as by conductor strip 271.

The body of the plug 265 also includes a skirt portion 272 having screw threads cooperating with the screw threads 217. There is an interior recess 273 in the skirt portion to receive the peripheral portions of the discs 233 and limit movement of the disc toward the plug body.

The body of the plug 265 as well as the ring 215, cylinder 226, and discs 230 and 233 are of suitable dielectric material or materials.

Associated, by way of example, with the plug 265 is an electric coupling K which is a conventional electric lamp socket having a central contact 280 and screw threads 281 forming the other contact and adapted to cooperate with the screw threads 266.

Upon screwing the plug 265 partly into the socket of the coupling K, the prongs 275 of the coupling H are inserted into the resilient socket means 45 as far as they will go. The ring 215 is held by one hand and the socket housing of the coupling K is held by the other hand, whereupon the connector G is rotated clockwise until the plug 265 is fully within the socket and tightened. This will cause the plunger 267 to force the wedging cylinder toward the disc 230 and, in turn, cause the means 45 to firmly grip the prongs 275, resulting in a good electrical and mechanical connection between the couplings H and K through the connector G.

Reversing the steps will permit the connector G to be detached from the couplings H and K.

Each of the three forms of the invention includes a rotatable operating ring, a wedging assembly including a wedging cylinder and two spaced apart discs or their mechanical equivalent with the cylinder between the discs and within the operating ring which latter has openings 60 with certain wall surfaces diverging toward one of the discs (which disc has prong receiving slots or the like aligned with the openings and the cylinder and discs being interconnected). The wedging cylinder carries resilient socket means 65 within the openings and protruding therefrom, which socket means is rigidly supported by the other of the discs (the support means, in each case, also providing electrical conductors). Means is provided to cause the wedging cylinder 70 to move toward and away from the first disc. Upon rotation of the operating ring and this movement of the wedging cylinder will cause the diverging walls to actuate the resilient socket means to either grip or release the prongs. The operating rings are in sliding contact with the

slotted discs which latter, however, are adapted to maintain fixed distances at all times with the other discs and provide dielectric closures or guards for the interior of the connectors as well as limit movements of the wedging cylinders in one like direction. The socket means, in each form, includes a pair of upset or swaged projections in a metallic strip, adapted to fit into the conventional openings in the prongs of electric plugs or caps and the hollows of the projections from sockets for portions of the socket means. Moreover, all the socket means are constructed and arranged to extend outwardly of the wedging cylinders at both like opposite faces thereof and contact the second discs which latter provide firm bases for the socket means.

Various changes may be made to the forms of the invention herein shown and described without departing from the spirit of the invention or scope of the claims.

What is claimed is:

1. A detachable electrical connector including a rotatable operating ring having means exteriorly thereof for grasping the ring for rotating the same; a wedging member assembly including a first disc provided with a pair of spaced-apart appliance plug prong-receiving elongated openings, a second disc spaced from and axially aligned with the first disc, a wedging cylinder in a part of the space between said discs and within said operating ring, and provided with a pair of spaced-apart socket means-receiving openings, the last mentioned openings having wall surfaces diverging toward said first disc, with one of said last-named openings axially aligned with the transverse axis of one of the first-named openings and the other of said last-named openings axially aligned with the transverse axis of the other of said first-named openings, resilient socket means to receive said prongs, including resilient wall portions, of electricity-conducting material, diverging towards said first disc, means interconnecting said wedging cylinder and discs, with said discs spaced apart a like distance at all times, and support means rigidly supporting said socket means upon said second disc to extend through said wedging cylinder and outwardly thereof towards said first disc, with said resilient wall portions in contact with the wall surfaces of said socket means-receiving openings; means to cause said wedging cylinder to move towards said first disc upon rotation of said operating ring in one direction and to move away from said first disc upon rotation of said operating ring in the other direction; and electrical conductor means electrically connected with said socket means.

2. A detachable electrical connector according to claim 1, characterized in that said rotatable operating ring is in sliding contact with one of said discs during rotation of said operating ring.

3. A detachable electrical connector according to claim 1, characterized in that the height of said operating ring is substantially greater than the height of said wedging cylinder, and the facing faces of said discs are spaced apart a shorter distance greater than the height of said wedging cylinder.

4. A detachable electrical connector according to claim 1, characterized in that said support means is of electricity conducting material and provides the electrical connection between said conductor means and said socket means.

5. A detachable electrical connector according to claim 1, characterized in that said resilient socket means also includes a pair of substantially

parallel resilient wall portions, connections between and spacing apart all of said wall portions, and a reinforcing member bearing against associated spaced-apart diverging and paralleling wall portions.

6. A detachable electrical connector according to claim 1, characterized in that said resilient socket means also includes a pair of substantially parallel resilient wall portions, connections between and spacing apart all of said wall portions, and a reinforcing member bearing against associated spaced-apart diverging and paralleling wall portions, and each of said substantially parallel wall portions facing another of said substantially parallel wall portions, and having a projection facing a like projection of the facing substantially parallel wall portion to be received in the conventional opening in a conventional electrical appliance prong.

7. A detachable electrical connector according to claim 1, characterized in that said resilient socket means also includes a pair of substantially parallel resilient wall portions, connections between and spacing apart all of said wall portions, and a reinforcing member bearing against associated spaced-apart diverging and paralleling wall portions, and each of said substantially parallel wall portions facing another of said substantially parallel wall portions, and having a projection and a socket with said projection facing a like projection of the facing substantially parallel wall portion to be received in the conventional opening in a conventional electrical appliance prong, and a member of resilient material bridging each associated diverging wall portion and parallel wall portion and extending into the socket of said parallel wall portion.

8. A detachable electrical connector according to claim 1, characterized in that said wedging cylinder has opposite substantially parallel outer faces, one facing one disc and the other facing the other disc, and said openings in said wedging cylinder extend from one of said faces to the other of said faces, and said socket means is constructed and arranged to extend outwardly of both faces and to contact said second disc at all times.

9. A detachable electrical connector according to claim 1 characterized in that one of the movements of said wedging cylinder is a rotary one and said means to cause said wedging cylinder to move comprises exterior screw threads of said wedging cylinder and interior screw threads of said operating ring.

10. A detachable electrical connector including a rotatable operating member having means exteriorly thereof for grasping the member for rotating the same; a wedging member assembly including a first disc provided with a pair of spaced-apart appliance plug prong-receiving elongated openings, a second disc spaced from and axially aligned with the first disc, a wedging element in a part of the space between said discs and within said operating member, and provided with a pair of spaced-apart socket means-receiving openings, the last-named openings having wall surfaces diverging toward said first disc, with one of said last-named openings axially aligned with the transverse axis of one of the first-named openings and the other of said last-named openings axially aligned with the transverse axis of the other of said first-named openings, resilient socket means to receive said prongs, including resilient wall portions, of electricity-conducting material, diverging towards said first disc, means interconnecting said wedging element

and discs, with said discs spaced apart a like distance at all times, and support means rigidly supporting said socket means upon said second disc to extend through said wedging element and outwardly thereof towards said first disc, with said resilient wall portions in contact with the wall surfaces of said socket means-receiving openings; means to cause said wedging element to move towards said first disc upon rotation of said operating member, in one direction and to move away from said first disc upon rotation of said operating member in the other direction; and electrical conductor means electrically connected with said socket means.

11. A detachable electrical connector according to claim 10, characterized in that said means to cause said wedging element to move comprises interior screw threads of said operating member and cooperating exterior screw threads of said wedging element.

12. A detachable electrical connector according to claim 10 characterized in that said electrical conductor means includes a plug associated with said second disc and having a body, electricity conducting screw threads for electrical connection with the interior screw threads of a conventional electric lamp socket and an electric terminal assembly for electrical connection with the conventional electric terminal of said conventional lamp socket.

13. A detachable electrical connector according to claim 10 characterized in that said electrical conductor means includes a plug rigidly carried by said second disc and having a body, electricity conducting screw threads for electrical connection with the interior screw threads of a conventional electric lamp socket and an electric terminal assembly for electrical connection with the conventional electric terminal of said conventional lamp socket.

14. A detachable electrical connector according to claim 10 characterized in that said electrical conductor means includes a plug rigidly carried by said second disc and having a body, electricity conducting screw threads for electrical connection with the interior screw threads of a conventional electric lamp socket and an electric terminal assembly for electrical connection with the conventional electric terminal of said conventional lamp socket, and said support means includes a rigid connection between said socket means, said second disc and said plug.

15. A detachable electrical connector according to claim 10 characterized in that said means interconnecting said wedging element and said discs comprises an elongated rigid member supporting said discs in fixed spaced apart relationship and with said wedging element movable along said rigid member.

16. A detachable electrical connector according to claim 10 characterized in that said means interconnecting said wedging element and said discs comprises an elongated axially disposed rigid member supporting said discs in fixed spaced apart relationship and with said wedging element rotatable with said rigid member.

17. A detachable electrical connector according to claim 10 characterized in that said electrical conductor means includes a plug associated with said second disc and having a body, electricity conducting screw threads for electrical connection with the interior screw threads of a conventional electric lamp socket and an electric terminal assembly for electrical connection with the conventional electric terminal of said conventional lamp socket, and said electric terminal assembly comprises a plunger slideable through said plug body, having an electrical terminal at its outer end and being rigid with said wedging element at its inner end, the last-named electric terminal being normally spaced from the outer end of said body, and resilient means normally urging said wedging element toward the second disc.

18. A detachable electrical connector according to claim 10 characterized in that said electrical conductor means includes a plug associated with said second disc and having a body, electricity conducting screw threads for electrical connection with the interior screw threads of a conventional electric lamp socket and an electric terminal assembly for electrical connection with the conventional electric terminal of said conventional lamp socket, and said electric terminal assembly comprises a plunger slideable through said plug body, having an electrical terminal at its outer end and being rigid with said wedging element at its inner end, the last-named electric terminal being normally spaced from the outer end of said body, and resilient means normally urging said wedging element toward the second disc, said resilient means comprising an expansion coil spring bearing at one end against the inner face of said first disc and at its other end against that portion of said wedging element most remote from said second disc.

MERVYN R. RATHBORNE.
